UNITED STATES PATENT OFFICE.

THOMAS H. KNUTH, OF NEW YORK, N. Y.

LACE-FASTENER.

SPECIFICATION forming part of Letters Patent No. 320,260, dated June 16, 1885.

Application filed March 31, 1885. (No model.)

To all whom it may concern:

Be it known that I, THOMAS H. KNUTH, a citizen of the United States, residing at New York, county and State of New York, have invented certain new and useful Improvements 5 in Lace-Fasteners, of which the following is a specification.

This invention relates to lace fasteners adapted to be used on shoes and other articles of 10 wearing-apparel.

The object of this invention is to so construct a lace-fastener that the several parts or bights of a lace will be uniformly and rigidly held thereby, as an improvement on lace-fasteners 15 heretofore made, which are adapted to hold one part only of a lace.

In making lace-fasteners to properly perform the above function, I so construct them with a spring-acting jaw or jaws that the gripping-surfaces 20 between which the lace is held will maintain their parallelism in all working positions, so as to firmly grip several parts or bights of the lace with a uniform pressure on all the parts or bights of the lace placed between them, 25 whatever the size of the lace may be.

The chief application of my fastener is to hold the bights or bows and free ends of laces when tied up out of the way, and prevent said tie from becoming loose, which loosening of the tie 30 is a source of much annoyance, and often happens when the laces are new or of a somewhat rigid nature.

In the accompanying drawings, forming part of this specification, to which I will now refer 35 to more clearly define the nature and construction of my invention—

Figure 1 represents the upper part of a shoe with my improved lace-fastener applied thereto. Figs. 2, 3, 4, and 5 are respectively a side 40 view, plan, cross-section on line $x-x$, and central longitudinal section of one of my improved lace-fasteners on an enlarged scale; and Figs. 6, 7, 8, and 9 are longitudinal sections of modifications.

To impart to lace-fasteners the feature of 45 maintaining the gripping-jaws parallel in all positions, I make the jaws with two spring-acting parts, arranged one at either end of the jaws; and I prefer to make the fasteners of a single piece cut out and stamped up from sheet 50 metal into the form shown in Figs. 2, 3, 4, and 5, in which the base-plate a has an eyelet, b ,

projecting down from its central part, by means of which the fastener is secured on the desired article in the ordinary way of securing by eyelets. 55

From opposite sides of the base-plate a are formed strips, which, when bent over the top of the base-plate, constitute spring-acting gripping-jaws c and d , the inner spring-jaw, c , being 60 forked or provided with horns c' at its free end, which embrace the sides of the spring-jaw d , and project beyond the same at its bend, so as to prevent the lace from passing under the spring c when placed between the jaws, as 65 shown at Fig. 2, e e representing the parts or bights of the lace. By an examination of this view, Fig. 2, with Fig. 5, which is shown free of the lace, it will be seen that the spring-jaws c and d are always parallel, the parts e e of the 70 lace, after they are passed between the bend of the spring c and the upwardly-bent end d' of the spring d , forcing the free end of the spring c down to the same extent that they force the free end of the spring d up, thus insuring a 75 uniform grip on all the parts of the lace that can be placed between the springs.

To insure the retention of the parts e e of the lace between the gripping-jaws of the springs c and d , a bend, c'' , is formed in the 80 spring c , which bend enters the pocket d' formed in the spring d when the fastener is empty, as shown at Fig. 5; but when the springs are separated, as shown at Fig. 2, the mouth of the gripping-jaws is constricted by the bend c'' . I 85 propose also to corrugate or form a bead or beads longitudinally along the springs c and d to add to their strength and make them more rigid, said corrugations or beads by being opposite on the gripping parts of the springs 90 bend or kink the parts of the lace, as shown at Fig. 4, so as to more firmly hold them against longitudinal strains. The beads may also extend around the base to stiffen it.

The application of my lace-fasteners to a shoe 95 is shown at Fig. 1, f representing the upper part of a shoe with lacing-hooks f' , and the lace e passed around the same and tied in a bow in the ordinary manner. The ends of the lace and bights of the bow are passed between the spring-jaws c and d of the fasteners, which are secured by means of their eyelets near the upper edge of the shoe, one at either side of the same. 100

It will be understood that my said fasteners

are adapted to hold and retain a single lace or one part of a lace, as well as several parts when the lace is short and fastened without forming a bow-tie; and also that they can be used on any article of wearing-apparel which is secured by means of a lace. In such cases where it is desired to remove the fastener from an article requiring washing or for other purposes, I propose to substitute for the eyelet *b* a threaded stem and nut, *b'*, as shown at Fig. 6.

The fasteners may be modified in construction without departing from my invention—as, for instance, in Fig. 6, the spring *g* forming the upper gripping-jaw may be bent backward onto itself at *g'*, so as to lay parallel with the lower jaw, *h*, the free ends of both springs being forked so as to embrace the bend of the spring *g*; or the lower spring-jaw may be omitted, as shown at Fig. 7, the top of the base *a* constituting the lower gripping-surfaces, the spring *i* having two bends, *i'* and *i''*, both of which yield when the lace is passed between the jaws, so that the jaw of the spring is always parallel with the fixed jaw of the fastener.

As an extra security to retain the lace between the jaws, the projection *j* is forced upwardly from the base *a* and enters an opening, *i''*, in the spring *i* when the jaws are in contact.

The springs may be made of wire. Fig. 8 shows a fastener with an upper spring-jaw, *k*, formed in one piece with the base, and a lower spring-jaw, *l*, formed of wire, secured in the base by placing its end in recesses formed by upward and downward depressions in the base, and held securely by suitably swaging or pressing the connection. The free end *l'* of the spring *l* passes through a slit formed in the bend of the spring-jaw *k*.

Fig. 9 represents a fastener in which the spring is formed of wire *m*, having two bends,

m' *m''*, adapted to act in a similar manner to the spring *i* of Fig. 7, said wire spring *m* being secured in the base of the fastener in the same manner as the spring *l*, Fig. 8.

Having now described my invention, what I claim, and desire to secure by Letters Patent, is—

1. As an article of manufacture, a lace-fastener having a base-plate, two springs bent over the top of the base-plate from opposite sides thereof, the adjacent sides of said springs constituting the gripping-jaws, and means for securing the base-plate to an article of wearing-apparel, substantially as set forth.

2. A lace-fastener consisting of the following parts in combination: the base *a*, the eyelet *b*, and the spring gripping-jaws *c* and *d*, bent over from opposite sides of the base *a*, substantially as and for the purpose set forth.

3. A lace-fastener composed of a single piece of metal, and consisting of the base *a*, spring-jaw *c*, having forked end *c'*, and upward bend *c''*, the spring-jaw *d*, having the pocket *d'*, and the eyelet *b*, or equivalent securing device, substantially as and for the purpose set forth.

4. A lace-fastener composed of a single piece of metal, and consisting of the base *a*, spring-jaw *c*, longitudinally corrugated and provided with bend *c''*, and the spring-jaw *d*, also longitudinally corrugated and provided with the pocket *d'*, substantially as and for the purpose set forth.

In testimony whereof I have hereunto set my hand, at New York, county and State of New York, this 28th day of March, 1885.

THOMAS H. KNUTH.
